[57] CLAIM

The ornamental design for a fifth wheel pin puller, as shown and described.

DESCRIPTION

FIG. 1 is a front elevational view of a fifth wheel pin puller, showing my new design, the rear view being a mirror image thereof;

FIG. 2 is a right side elevational view thereof;

FIG. 3 is a bottom plan view thereof;

FIG. 4 is a top plan view thereof;

FIG. 5 is a left side elevational view thereof;

FIG. 6 is an inverted front elevational view thereof, shown on a reduced scale; and,

FIG. 7 is a perspective view thereof, the broken line portion being for illustrative purposes only and forming no part of the claimed design.

FIGS. 1 through 6 are shown fragmentarily for ease of illustration.
